BULL BLOCK STRINGUP MECHANISM

Carl O. Bruestle, Rahway, N. J., assignor to
Synchro Machine Company, Rahway, N. J., a
corporation of New Jersey

Application March 13, 1942, Serial No. 434,547

6 Claims. (Cl. 242—79)

This invention is concerned with an improved structure forming part of the bull or coiler block mechanism commonly employed with wire drawing machines by means of which the initial end of the wire to be drawn is readily attached to the bull or coiler block and which functions so as to permit, contrary to the present practice, the continuous operation of the machine from the beginning to the end of the formation of the coil.

Under the more common practices today in the wire drawing and coiling art, the initial end of the wire to be drawn and coiled is attached to the block by means of a clamp having a chain which is in turn secured to the block for the first few turns of wire applied thereto. In accordance with one practice after a few turns have been wound onto the block the machine is stopped, the clamp and chain removed, and the end of the wire attached to some available part of the block in the case of light wire or to a special clamp on the block in the case of heavy wire or wire of high tensile strength. In the latter case at the end of the coiling operation the end of the wire must be retrieved from within the coil before the coil can be stripped from the block. This is a time consuming operation which is eliminated by this invention.

In accordance with this invention a portion of the attached mechanism forms part of the bull or coiler block while the remainder is separable therefrom in a manner so that it rides upwardly on top of the coil as the coil is formed. The result is that this latter portion is exposed and easily removed after the coil is finished.

An important advantage of the arrangement of this invention is that at once the machine is started after the end of the wire is attached the complete coil is formed before it is necessary to again bring it to a stop.

The full nature and scope of this invention will be best appreciated by the following detailed description of one embodiment thereof as illustrated in the attached drawings.

This invention resides substantially in the combination, construction, arrangement and relative location of parts, all as will be described in detail below.

In the accompanying drawings in which the same reference numerals will be used throughout the various views to show the same or similar parts,

Figure 1 is a side elevational view of those parts of a wire drawing machine and coiling or bull block necessary to an illustration of the invention showing the relation of the parts after

the initial end of the wire is attached to the bull block and the machine is ready to be started;

Figure 2 is a top plan view of the mechanism of Figure 1;

Figure 3 is a side elevational view similar to that of Figure 1 showing the position of the parts after the bull block has rotated through about ninety degrees from its initial position;

Figure 4 is a top plan view of the mechanism of Figure 3 showing the same relationship of parts;

Figure 5 is a view of the bull block corresponding to that of Figure 4 with some parts broken away and some parts shown as a result in section;

Figure 6 is an enlarged vertical cross-sectional view through the portion of the bull block with which this invention is concerned showing how the latching mechanism is held in unlatched position; and

Figure 7 is a view similar to Figure 6 showing how the latch is operated into latched position.

In the drawings there is illustrated at 1 a very small portion of a wire drawing machine at the region of its finishing die. The finishing die is diagrammatically illustrated at 2 mounted in a suitable die holder 2. The initial end W of the wire is shown projecting through the finishing die. The bull or coiler block driving mechanism in accordance with common practice is mounted within a housing the outline of the top of which is indicated at 4. The vertical shaft for the block is indicated at 5 and mounted on its upper end is the block itself consisting of the vertical tapered portion 6 and the integral radial flange portion 7 illustrating their surfaces merging in the usual fillet 8. Mounted upon the block adjacent the stripper slots 9 are the vertical extension rods or bars 9' commonly forming a part of a bull or coiler block.

In accordance with this invention a portion of the tapered cylindrical part 6 of the block is formed of a longitudinally curved arm 10 pivotally mounted on the bull block at 11. In length the arm 10 forms a 90° segment of the cylindrical surface 6 and in closed position as indicated in Figures 3 and 4 the arm 10 fits snugly within a similarly shaped opening in the cylindrical portion 6 and forms a continuation of the surface thereof. As indicated in Figure 1 the lower edge of the arm 10 is inclined at an angle to the axis of the block so that the slot formed between it and the bull block is inclined to the longitudinal axis of the wire as it is coiled thereon. This serves to overcome any tendency of the wire to be injured in the event that the arm 10 does

not completely close the opening at its lower edge. This problem is not present at the upper edge of the arm because by the time the wire reaches that elevation it is not under any tension.

The free end of the arm 10 is provided with a vertical T-shaped slot 12 as appears clearly in Figure 2 and receives a T-shaped block 13 which loosely fits therein so as to be free to slide vertically in the slot 12. Pivotedly mounted at 15 on the block 13 is a link 14 which in turn pivotally supports a suitable clamp 17 on the horizontal pivot pin 16. This combination of supports provides a substantially universal motion connection. The clamp 17 may be of any construction suitable for the purpose and adapted to easily receive and firmly grip the initial end of the wire W as is clear from the drawings.

When the arm 10 is in closed position its slot 12 is in alignment with the vertical slot 6' of similar cross-sectional shape formed in the portion 6 of the block as is best seen from Figure 6.

Mounted on the upper face of the block by means of a foot plate 18 is a vertical standard 19 which likewise has a T-shaped slot 20 formed throughout the length thereof. The standard 19 is attached in place so that its slot 20 is in alignment with the slot 6'. Thus the slots 12, 6' and 20 provide a continuous vertical channel open at one side in which the T-shaped block 13 may freely slide.

Pivotedly mounted within the block on a pivot pin 22 is a latch 21 which is normally latched upwardly by a spring 23 (see Figure 6). The latched end is positioned so that it may project upwardly into the lower end of the slot 12 but is caused to be ejected therefrom by means of the block 13 when it is in its initial or lowermost position.

In order to thread or string up a device constructed in accordance with this invention the block or coiler block is positioned with respect to the finishing die, as indicated in Figures 1 and 2, so that when the arm 10 is in extended position it points towards the finishing die 3. The block 13 with attached parts is mounted in the T-shaped slot 12. The initial end of the wire W projects through the finishing die 3 sufficiently so that it may be securely attached in the clamp 17. The machine is then operated so that the block rotates in a counterclockwise direction (Figure 2). Upon the first quarter turn of the block the arm 10 moves from extended position into the opening in the portion 6 of the block to the position shown in Figures 3 and 4 where its outer face is flush with the surface of the portion 6 and forms a continuation thereof. At this time the latch 21 is in the position as shown in Figure 6, being held there by the weight of the block 13 and attached parts. Further rotation of the block causes the wire W to be drawn around it so that ultimately, in accordance with usual practice, the wire engages the block in the fillet 8 and each succeeding turn forces the preceding turns upwardly ahead of it, as will be clear from Figure 7. As the initial turn is forced upwardly, being in engagement with the lower surface of the block 13, it causes it to move slowly upwardly in the T-shaped passage 12-6'-20. After very little vertical movement of the block 13, latch 21 is freed so that the spring 23 may move it into latched position in the lower end of slot 12, and thereby lock the arm 10 in closed position until released. As the coil builds up the block 13 with attached parts rides slowly upwardly on the standard 19 so as to approach the

top thereof at the time a full coil has been completed.

At the end of the formation of the coil the machine is stopped and the initial end of the wire 5 is removed from the clamp 17 very quickly and easily because of the fact that the clamp is in an exposed position. This is contrary to the same prior practice where it is necessary to reach down inside of the coil to release the end of the wire. 10 After the wire is released the block 13 with attached parts is lifted out of the upper end of the slot 20 and the completed coil may then be stripped from the machine in accordance with the usual practice. When the block is put back into the slot and moved to the lower end thereof it releases the latch 21 so that the arm 10 can again be swung out for attachment to a new end of the wire.

The mechanism of this invention is particularly 20 adapted to the handling of heavy wire sizes, and especially heavy wire made of steel, such as high carbon steel. The handling of heavy high carbon steel wire is a difficult task at best, but the structure of this invention greatly facilitates the operation of drawing and coiling wires of this nature.

With the usual chain and clamp arrangement 25 the surface of the drawing portion of the block becomes scored which is, of course, undesirable. It will be apparent that by reason of the construction herein disclosed, there is no longer any danger of scoring the drawing face of the block.

As will be readily appreciated by those skilled 30 in this art, the novel subject matter of this invention is capable of embodiment in other physical forms representing structural modifications of that employed for purposes of illustration.

Those skilled in this art will appreciate that 35 this mechanism is not necessarily limited in its use to the handling of steel wires or even wires of nonferrous materials, but is capable of application in the handling of strands of various materials and of various cross-sections.

I do not, therefore, desire to be strictly limited 40 to the single embodiment of the invention as disclosed herein, but rather by the scope and range of equivalents of the claims appended hereto.

What is claimed is:

1. In a strand coiling mechanism the combination including a block having a coil receiving portion, an arm pivotally mounted on the block and forming in closed position a part of the coil receiving portion, a slot in the end of said arm, means mounted on the block forming an extension of said slot, and a strand clamping device slidably mounted in said slot and its extension.
2. In a strand coiling mechanism the combination including a block having a coiling portion, an arm pivotally mounted on the block and forming in closed position a part of the coiling portion, a slot in the end of said arm, means mounted on the block forming an extension of said slot, a strand clamping device slidably mounted in said slot and its extension, and means for locking said arm in closed position.
3. In a strand coiling mechanism the combination including a block having a coiling portion, an arm pivotally mounted on the block and forming in closed position a part of the coiling portion, a slot in the end of said arm, means mounted on the block forming an extension of said slot, a strand clamping device slidably mounted in said slot and its extension, and means released by said clamping device as it moves from

its initial position for locking the arm in closed position.

4. In a wire coiling machine the combination comprising a block having a cylindrical portion having a radial circumferential flange at one end, the surface of the cylindrical portion and the flange uniting in a fillet, said cylindrical portion having an arcuate recess in the face thereof, a longitudinally curved arm pivotally mounted at one end in the recess and completing the surface of the cylindrical portion when lying in the recess, said arm having a guideway at its free end, means forming a guideway in alignment with the guideway in said arm, and a strand clamping device mounted in the guideway for sliding movement therein.

5. In a wire coiling machine the combination comprising a block having a cylindrical portion having a radial circumferential flange at one end, the surface of the cylindrical portion and the flange uniting in a fillet, said cylindrical portion having an arcuate recess in the face thereof, a longitudinally curved arm pivotally mounted at one end in the recess and completing the surface

of the cylindrical portion when lying in the recess, said arm having a guideway at its free end, means forming a guideway in alignment with the guideway in said arm, a carrier slidably mounted in the guideway, a strand gripping device, and means for pivotally mounting the gripping device on said carrier.

6. In a wire coiling mechanism the combination comprising a cylindrical coiler having a radial circumferential flange at one end, the surface of the cylindrical coiler and the flange uniting in a fillet, said cylindrical coiler having an arcuate recess in the face thereof, a longitudinally curved arm pivotally mounted at one end in the recess and completing the surface of the cylindrical coiler when lying in the recess, said arm having a guideway at its free end, means forming a guideway in alignment with the guideway in said arm, a carriage slidably mounted in the guideway, a strand gripping device, means for pivotally mounting the gripping device on said carriage, and a latch for locking the arm in the recess.
